SCAFFOLD HANGER

Henderson G. Leonard, Box 128, Covert, Mich.

Filed June 19, 1959, Ser. No. 821,544

8 Claims. (Cl. 248—324)

This invention relates to improvements in scaffold hangers. The principal objects of this invention are:

First, to provide a novel form of scaffold hanger for securely supporting a workman's scaffold from an overhead beam or truss which hanger is adjustable to fit various sizes of supporting beams.

Second, to provide a scaffold hanger having adjustable divergent beam engaging hooks that are held against collapse by a hand rail supporting bracket on the scaffold hanger.

Third, to provide a scaffold hanger which is adjustably engageable with supporting beams of different sizes and lockably rollable in adjusted position to prevent accidental disengagement from the beam.

Fourth, to provide a scaffold hanger having spaced beam engaging arms tied together to move concurrently along a supporting beam and having a winch and lift cable mounted between the arms with the cable guided by the tie between the arms for hoisting the hanger to position.

Fifth, to provide a scaffold hanger which is simple to adjust and relatively inexpensive to manufacture and yet is rugged and positive in its supporting engagement with the supporting beam.

Other objects and advantages of the invention will be apparent from a consideration of the following description and claims. The drawings, of which there are two sheets, illustrate a highly practical form of the scaffold hanger.

Fig. 1 is a fragmentary side view of the scaffold hanger of the invention.

Fig. 2 is a fragmentary cross sectional view taken along the plane of the line 2—2 in Fig. 1.

Fig. 3 is a fragmentary end elevational view of the hanger.

Fig. 4 is a fragmentary cross-sectional view taken along the plane of the line 4—4 in Fig. 3.

Fig. 5 is a fragmentary cross-sectional view illustrating the locking engagement between the hand rail support and the divergent beam engaging arms of the hanger taken along the plane of the lines 5—5 in Fig. 3.

In the erection and maintenance of overhead structures such as bridges and roofs it is often necessary to support a platform underneath the structure on which workmen may stand while working on the structure overhead. This has been done by means of scaffold hangers that engage a beam or truss of the structure and hang therebelow to support a foot plank or scaffold for the workmen to stand on. It will be appreciated that two scaffold hangers engaged with spaced beams or trusses are employed to support the opposite ends of the scaffold or platform but only one of the scaffold hangers is illustrated herein.

The hanger comprises a U-shaped support shown in part in Fig. 1 and including a horizontal bar 1 adapted to support a scaffold platform and upright arms 2. Near the upper ends of the arms 2 a pair of divergent bars 3

2

are connected to the arms by bolts 4 passed through selected holes in the arms. The upper ends of the divergent bars 3 have angled clips 5 secured thereto forming bifurcated ends on the divergent bars with pivot pins 6 supported across the bifurcations. The pivot pins 6 angularly adjustably connect the lower ends of angled hook members 7 to the divergent bars. The upper ends of the hook member 7 have oppositely inwardly turned pindle portions 8 on their upper ends which rotatably receive and support rollers 9. Rigidly secured to each hanger member 7 as by welding and projecting inwardly therefrom in opposed overlapping relation to the corresponding part on the other hanger member is a spreader bar 10 having a loop or ferrule 11 on its projecting end and defining a series of transverse holes 12. The ferrule 11 on one spreader bar embraces the other spreader bar and holds the bars in straight overlapping but longitudinally adjustable relation. A pin 13 is passed selectively through the holes 12 to determine the spacing between the upper ends of the hanger member 7 and the rollers 9.

Vertically adjustably mounted on each upright arm 2 above the point of connection of the divergent bars 3 thereto is a loop or sleeve 14 having an outwardly and upwardly angled bracket 15 on its outer side. The sleeve 14 is adapted to be clamped to the upper end of the arm 2 by a set screw 16 with the lower edges of the sleeve in abutting engagement with the divergent bars 3 as indicated at 17 in Fig. 3. The brackets 15 are adapted to support the ends of hand rails shown in phantom at 18 that extend in parallel relation above a platform supported on the crossbar 1.

From the foregoing description it will be apparent that by loosening the clamp screws 16 and raising the sleeves 15 and also removing the pin 13 the angled hook member 7 and the rollers 9 carried thereby can be spread further apart or moved closer together depending upon the size of the beam over which the rollers 3 are to be hooked. The spreading adjustment of hook member 7 permits easy installation of the hangers on the beam by permitting the rollers to be engaged over the opposite edges of the beam and then drawn close together so that the rollers and hooks cannot be accidentally disengaged from the beam. The lock pins 13 are then passed through the holes 12 in the overlapping spreader bars and the sleeves 14 are moved downwardly into blocking engagement between the lower ends of the divergent bars 3 and clamped in place by clamp screws 16. The lower crossbar 1 is in position to safely support a scaffold platform and the brackets 15 are ready to support spaced hand rails.

In the operative position of the hanger the spreader bars 10 primarily prevent accidental spreading of the hook member 7 and consequent disengaging of the rolls from the supporting beam. In addition, the blocking engagement of the sleeves 14 between the divergent bars 3 prevents downward tension applied to the connecting bolt 4 from drawing the divergent bars 3 and the pins 6 at their upper end closer together thus spreading the rollers 9. The load on the scaffold is thus safely and approximately equally distributed between the four rollers 9 and the pivot pins 6 so that a safe and stable support for the scaffold is provided.

The hanger structure thus far described is entirely adequate for securely and safely supporting a scaffold from a beam, but in order to facilitate the raising and lowering of the scaffold with or without workmen thereon and for temporarily relieving the load on the rollers 9 and angled hanger members 7 for shifting the scaffold along the support beam, a winch indicated in its entirety at 19 is supported between the upright arms 2 of the U-shaped support. The winch is connected to the U-shaped support

by downwardly divergent straps 20 connected to the winch by a pivot pin 21. In order to hold the straps 20 upright their lower ends are provided with downwardly turned tabs 22 with outwardly facing U-shaped clips 23 secured thereto. These clips embrace the edges of the upright arms 2 and connecting screws 24 are passed through holes provided therefor in the upright arms and threaded into the base of the clips. Since the main load applied to the straps 20 is vertically upward, the channel shaped clips 23 and screws 24 are sufficient to hold the divergent straps in upwardly extending position between the arms 2.

The cable 25 from the winch is extended upwardly to a suitable hook 26 that can be attached to an eye bolt 27 carried by a temporary supporting clamp 28 engageable over the flanges of a beam such as is indicated at 29 from which the scaffold is to be supported. The clamp 28 is relatively small and light and can be installed or removed by means of a long pole prior to attaching the scaffold and scaffold hanger thereto. Alternatively the clamp 28 can be installed from above by someone standing on the beam. With the clamp 28 and cable 25 connected to the beam workmen may stand on the scaffold and operate the cranks 30 of the winches carried by the hangers at each end of the scaffold to raise the scaffold and themselves to the operative position of the scaffold. The clamps 28 do not provide sufficient security and safety to support the scaffold as the workmen move around in the performance of their duties but after the angled hanger members 7 and rollers 9 are engaged with the beam as previously described the scaffold is firmly and safely supported for free movement of the workmen on the scaffold.

In order to prevent lateral flexing of the upright bars 2 as the hanger is moved along the supporting beam a tie bar 31 is extended between the upper ends of the bars 2 and provided with outwardly facing U-shaped clips 32 on its ends which embrace the edges of the bars 2 as appears most clearly in Fig. 4. A stud 33 is passed through the base of U-shaped clip and threaded into the tie bar as its outer end is projected through a hole provided therefor in the upright bar 2 and clamped in place by the wing nut 34. The tie bars 31 may also carry U-shaped clips 35 secured in concavely facing relation to the sides of the tie bar by bolts 36 to form a guide and retaining channel for the upwardly extending reach of the cable 25 connected to each hanger. The tie bar 31 thus performs the dual function of tying the upright bars 2 together and guiding the cable 25 so that the cable will be held in upwardly extended position and will support the winch 19 against swinging downwardly about the pivot pin 21 when the cable is not under tension.

What is claimed as new is:

1. A scaffold hanger comprising a U-shaped support having upright arms with divergent bars pivotally connected to their upper ends and swingable in parallel planes perpendicular to the plane of the U-shaped support, angled hanger members pivotally connected to the upper ends of said divergent bars and having inwardly directed pintles on their upper ends with rollers thereon, spreader bars rigidly connected to said angled hanger members and projecting inwardly in overlapping relation with the spreader bar on the opposed hanger member, means forming guides on said spreader bars holding the lapped bars in lapped relation, said spreader bars defining holes selectively positioned in registering relation, pins passed through registering holes in said spreader bars, a winch positioned between said upright arms and connected thereto by downwardly divergent straps, said straps having U-shaped clips on their lower ends embracing the edges of said upright arms to prevent lateral tilting of the straps, a cable carried by said winch and adapted to extend thereabove to a beam engaging clamp, a tie bar extending transversely between the upper ends of said upright arms and having U-shaped clips on its

ends embracing the edges of said upright arms, and a U-shaped angled clip secured in concavely facing relation to the side of said tie bar and defining a guideway passing the cable of said winch, the upper ends of said upright arms having sleeves adjustably slideable thereon between said tie bar and the pivotal connections between said divergent bars and said upright arms with means for clamping said sleeves in blocking engagement with the divergent edges of said divergent bars, said sleeves having hand rail engaging brackets mounted on their outer sides.

2. A scaffold hanger comprising a U-shaped support having upright arms having vertically spaced holes therein, a hanger selectively connected to each arm by a bolt passed through one of said holes and comprising divergent bars engaged with the bolt, beam engaging hooks pivotally connected to the upper ends of said divergent bars and having opposed inwardly extending pintles on their upper ends, rollers rotatably mounted on said pintles, spreader bars fixedly secured to said hooks and projecting inwardly into overlapped relation, ferrules on each spreader encircling the overlapping spreader, and means selectively connecting said spreaders in selected degrees of overlap to adjustably fix the spacing of said hooks and said rollers, and hand rail supports encircling said upright arms and adapted to be clamped thereto in abutted relation between said divergent bars to obstruct collapsing movement of the divergent bars.

3. A scaffold hanger comprising a U-shaped support having upright arms having vertically spaced holes therein, a hanger selectively connected to each arm by a bolt passed through one of said holes and comprising divergent bars engaged with the bolt, beam engaging hooks pivotally connected to the upper ends of said divergent bars and having opposed inwardly extending pintles on their upper ends, rollers rotatably mounted on said pintles, spreader bars fixedly secured to said hooks and projecting inwardly into overlapped relation, a ferrule on one spreader encircling the other overlapping spreader, and means selectively connecting said spreaders in selected degrees of overlap to adjustably fix the spacing of said hooks and said rollers, and annular members encircling said upright arms and adapted to be clamped thereto in abutted relation between said divergent bars to obstruct collapsing movement of the divergent bars.

4. A scaffold hanger comprising a hanger bar having vertically spaced holes therein, divergent bars engaged with a pin through one of said holes on opposite sides of the hanger bar, beam engaging hooks pivotally connected to the upper ends of said divergent bars and having opposed inwardly extending pintles on their upper ends, rollers rotatably mounted on said pintles, spreader bars fixedly secured to said hooks and projecting inwardly into overlapped relation, ferrules on each spreader encircling the overlapping spreader, a pin selectively connecting said spreaders in selected degrees of overlap to adjustably fix the spacing of said hooks and said rollers, and an annular member encircling said hanger bar and adapted to be clamped thereto in abutted relation between said divergent bars to obstruct collapsing movement of the divergent bars.

5. A scaffold hanger comprising a hanger bar having vertically spaced holes therein, divergent bars with a pin through one of said holes, beam engaging hooks pivotally connected to the upper ends of said divergent bars and having opposed inwardly extending pintles on their upper ends, rollers rotatably mounted on said pintles, spreader bars fixedly secured to said hooks and projecting inwardly into overlapped relation, a ferrule on one spreader encircling the overlapping spreader, a pin selectively connecting said spreaders in selected degrees of overlap to adjustably fix the spacing of said hooks and said rollers, and an annular member encircling said hanger bar and adapted to be clamped thereto in abutted

relation between said divergent bars to obstruct collapsing movement of the divergent bars.

6. A scaffold hanger comprising a U-shaped support having upright arms with divergent bars pivotally connected to their upper ends and swingable in parallel planes perpendicular to the plane of the U-shaped support, angled hanger members pivotally connected to the upper ends of said divergent bars and having inwardly directed pintles on their upper ends with rollers thereon, spreader bars rigidly connected to said angled hanger members and projecting inwardly in overlapping relation with the spreader bar on the opposed hanger member, means forming guides on said spreader bars holding the lapped bars in lapped relation, said spreader bars defining holes selectively positioned in registering relation, pins passed through registering holes in said spreader bars, a winch positioned between said upright arms and connected thereto by downwardly divergent straps, a cable carried by said winch and adapted to extend thereabove to a beam engaging clamp, a tie bar extending transversely between the upper ends of said upright arms, the upper ends of said upright arms having sleeves adjustably slid-
able thereon between said tie bar and the pivotal connec-
tions between said divergent bars and said upright arms
with means for clamping said sleeves in blocking engage-
ment with the divergent edges of said divergent bars.

7. A scaffold hanger comprising a U-shaped support having upright arms with divergent bars pivotally connected to their upper ends and swingable in parallel planes perpendicular to the plane of the U-shaped support, angled hanger members pivotally connected to the upper ends of said divergent bars and having inwardly directed pintles on their upper ends with rollers thereon, spreader bars rigidly connected to said angled hanger members and projecting inwardly in overlapping relation with the spreader bar on the opposed hanger member, means forming guides on said spreader bars holding the lapped bars

in lapped relation, said spreader bars defining holes selec-
tively positioned in registering relation, pins passed
through registering holes in said spreader bars, a winch
positioned between said upright arms and connected
thereto by downwardly divergent straps, a cable carried
by said winch and adapted to extend thereabove to a
beam engaging clamp, a tie bar extending transversely
between the upper ends of said upright arms, the upper
ends of said upright arms having sleeves adjustably slid-
able thereon between said tie bar and the pivotal connec-
tions between said divergent bars and said upright arms
with means for clamping said sleeves in blocking engage-
ment with the divergent edges of said divergent bars.
8. A scaffold hanger comprising a U-shaped support
having upright arms with divergent bars pivotally connected to their upper ends and swingable in parallel planes perpendicular to the plane of the U-shaped support, angled hanger members pivotally connected to the upper ends of said divergent bars and having inwardly directed
pintles on their upper ends with rollers thereon, spreader bars rigidly connected to said angled hanger members and projecting inwardly in overlapping relation with the spreader bar on the opposed hanger member, means forming guides on said spreader bars holding the lapped bars in lapped relation, said spreader bars defining holes selectively positioned in registering relation, pins passed through registering holes in said spreader bars, a tie bar extending transversely between the upper ends of said upright arms, the upper ends of said upright arms having sleeves adjustably slid-
able thereon between said tie bar and the pivotal connec-
tions between said divergent bars and said upright arms
with means for clamping said sleeves in blocking engage-
ment with the divergent edges of said divergent bars.
